United States Patent Office

Des. 232,129

Patented July 16, 1974

232,129

TOOL BOX OR SIMILAR ARTICLE

Jack Evans, Flossmoor, Ill., assignor to J. E. Industrial
Molding Inc., Grant Park, Ill.

Filed Aug. 18, 1972, Ser. No. 281,989

Term of patent 14 years

Int. Cl. D3—01

U.S. Cl. D87—1 R

FIG. 1 is a perspective view of a tool box, or similar article, showing my new design;

FIG. 2 is a top plan view thereof;

FIG. 3 is a front elevational view thereof;

FIG. 4 is an end elevational view thereof;

FIG. 5 is a rear elevational view thereof; and

FIG. 6 is a bottom plan view thereof.

I claim:

The ornamental design for a tool box or similar article, as shown.
